UNITED STATES PATENT OFFICE.

JUSTUS FEYER, OF BARMEN, GERMANY.

DRIVING MECHANISM.

1,132,174.

Specification of Letters Patent. Patented Mar. 16, 1915.

Application filed September 14, 1911. Serial No. 649,282.

To all whom it may concern:

Be it known that I, JUSTUS FEYER, a subject of the German Emperor, and residing at Barmen, Rhenish Prussia, Germany, have 5 invented certain new and useful Improvements in Driving Mechanism, of which the following is a full and clear specification.

The object of my invention is to provide an electric motor for driving looms and the 10 like machines and it consists in the arrangement and use of constructions for journaling the motor so that the same may not find solely a resistance in the machine which should be driven but also in another element forming a force accumulator in order 15 that a great equality in the motion of the machine may be obtained.

With the above and other objects in view my invention consists in the novel construction and arrangement of parts illustrated 20 in the accompanying drawings, in which—

Figure 1 is a side view of the complete driving device for a loom, Fig. 2 is a similar view of a modified construction, Figs. 3 25 and 4 are modified details of construction of said device and Fig. 5 another modification from which Fig. 6 is a detail. Fig. 1^a illustrates a detailed view of the coil spring.

Like letters of reference indicate like parts 30 in the drawings.

Referring to Fig. 1 the reference numeral 1 is an electric motor of any suitable construction which is fastened to a holder or arm 2 that is loosely fitted on a shaft 3 which shaft is at the same time the driving shaft of a loom or other working machine with irregular working speed and force. On 35 said shaft 3 is keyed a gear wheel 4 which is in mesh with a gear 5 on the motor shaft 6. The whole device is mounted on a standard 7. On one end of the shaft 10 there is a head 12 which is pivotally connected to the motor 1. A sleeve 9 carrying the collar 8 is rotatably mounted on the shaft 10. The 40 said collar, operates in the groove 7' of the standard 7, which collar forms a guide for the shaft 10. On the free end of the shaft 10 is mounted a washer 11 which is held thereon by the nut 15, the said washer forming 45 a stop for one end of the coil spring 13; the opposite end of the spring engaging the collar 8 for restricting movement thereof. When starting the motor by feeding it with electric power the same will turn 50 around its suspension point 3 until the resistance of the loom and the spring is in ac-

cordance with the turning moment of the motor which is pending on the shaft 3. If the resistance of the loom is diminished the motor is turned in contrary direction by 60 means of the spring, the nut 15 being provided for regulating the tension of the same. It may be pointed out, that the spring may have any convenient form or shape, so for instance it may be shaped or coiled of 65 square-shaped wire or made conically as shown in Fig. 1^a. In the latter case it may better resist the forces developing in the loom.

In Figs. 2, 3 and 4 a modification of my 70 invention is illustrated. In this construction to the shaft 3 is keyed a box 16 extending in an arm 2 with which is connected the motor 1 the shaft 6 of which carries again the gear 5 being in mesh with the gear 4 that 75 is loosely mounted on shaft 3. The said box 16 is surrounded by a brake band 17 extending in the pieces 18 that may be screwed together by a set screw 19 allowing thus to regulate the action of the brake. The box 80 16 forms part of an arm 2 on which is fastened a rod 20 in a suitable manner which carries a weight 21 as will be seen and as will be understood from the foregoing the motor may pend also on said shaft 3 and 85 the weight in combination with the brake may regulate the irregular working forces in the loom or other machine, which in this case is driven by the gear 4. To improve the action of the arrangement of parts, I 90 insert in the interior of the box 16 spirally wound springs 22 one end of which is in connection with the inner wall of the box and the other is inserted in a slot 23 of the shaft 3. A lid 24 fastened to the box with screws 95 24^a protects the springs as shown. It may be mentioned, that the weight may be also arranged to slip to and fro on its rod for the purpose of regulating the working action 100 of the parts.

In Figs. 5 and 6 another modification of my machine is illustrated. The motor 1 is connected with a box 26 seated on shaft 3 by means of a screw 27 and corresponding nuts and it may be lowered or raised by said 105 screw in order to conveniently change the gears 4 and 5. The box is closed on both sides by lids 28. Within said box or casing 26 are located two boxes 29, and 30 having lateral segmental recesses 31, and 32 which 110 project through the said lids 28 and with said recesses engage the set rings 33, 34

provided with sector like protuberances 35, 36 for this purpose. On said boxes 29, 30 the casing 26 and motor 1 are rotatably mounted. Ball bearings not shown in the drawing may be used to support the oscillating movement of the motor. In the casing 26 are arranged coil springs 37, one end of each of said coil springs being fixed to the casing, and the opposite ends of the 10 springs being secured to the boxes 29 and 30, the said springs being so arranged that when the motor is in operation the said springs expand. By making the springs of thicker or thinner wire or by inserting 15 a corresponding number of springs the resistance of the loom may be accordingly regulated. In order to avoid a sudden contrary motion of the motor, a second set of springs 38 may be incorporated 20 in the casing 26 which receives the shocks of the motor.

What I claim and desire to secure by Letters Patent is.

1. A driving mechanism for looms comprising a frame, a shaft journaled in the frame, a rod depending from the shaft, a motor carried by the rod, a second shaft having one end thereof pivotally secured to the motor, a sleeve rotatably mounted on the 25 second mentioned shaft, a collar on the sleeve, and means between the collar and 30

opposite end of the second mentioned shaft for receiving the initial movement of the motor.

2. In a driving mechanism, a frame, a 35 shaft supported by the frame, a motor supported by the shaft, a groove in the frame, a rod pivotally secured to the motor, means on the rod for receiving the initial movement of the motor, and means carried by the 40 rod for engaging the walls of the groove for guiding the rod.

3. A driving mechanism for looms comprising a frame, a motor supported by the frame, a rod associated with the motor, 45 means on the rod for receiving the initial movement of the motor, and means on the frame for restricting the movement of the rod.

4. A driving mechanism comprising a 50 frame having a groove, a motor supported by the frame, a rod having one extremity pivotally connected to the motor, a collar on the rod, the collar adapted to move in the groove, and resilient means between the opposite end of the rod and collar for receiving 55 the initial movement of the motor.

JUSTUS FEYER. [L. S.]
